EAVES TROUGH DRAIN STRAINER

Carl L. Weyand, Waterbury, Conn.

Application March 8, 1934, Serial No. 714,542

5 Claims. (Cl. 210—170)

This invention relates to strainers, and more particularly to a strainer adapted for use in a drain pipe or down spout of an eaves trough or drain gutter.

One object of this invention is to provide an improved drain pipe strainer comprising a plurality of ribs having straight lower sections and outwardly curved or bowed upper sections, so arranged as to form a cage, cylindrical at the bottom and dome-shaped at the top.

A further object is to provide a strainer of the above nature in which each rib is made from a flat longitudinal strip of sheet metal bent into U-shape or channel cross-section.

A further object is to provide a strainer of the above nature in which the upper ends of the ribs have tongues which are bent around a flat apex ring, and said ribs are uniformly spaced apart at the lower cylindrical section of the strainer by a ring of channel-shaped cross-section, to which the ribs are interlocked to produce a rigid construction.

A further object is to provide a strainer of the above nature which will be simple in construction, inexpensive to manufacture, easy to install and manipulate, compact, ornamental in appearance, and very efficient and durable in use.

With these and other objects in view, there have been illustrated on the accompanying drawing two forms in which the invention may be conveniently embodied in practice.

In the drawing:

Fig. 1 represents a perspective view of the first form of down spout strainer embodying the invention.

Fig. 2 is a fragmentary top plan view of the same.

Fig. 3 is a fragmentary detail perspective view of the lower spacing ring and attached ribs.

Fig. 4 is a longitudinal sectional view of the upper section of one of the ribs, the view being taken along the line 4—4 of Fig. 2.

Fig. 5 is a plan view of the flat apex ring adapted to be connected to the upper ends of the ribs.

Fig. 6 is a perspective view of one of the ribs as it appears before assembly.

Fig. 7 is a fragmentary perspective view, similar to Fig. 3, of a modified form of lower spacing ring.

Referring now to the drawing in which like reference numerals denote corresponding parts throughout the several views, the numeral 10 indicates generally the cage-like down spout strainer, which has an upper substantially spherical dome-shaped portion 11 and a lower cylindrical portion 12 adapted to fit in the down spout of an eaves trough. The strainer device is constructed from a plurality of guard members or ribs 13, preferably made from flat sheet metal strips and formed into U-shaped or channel cross-section, the upper portion of each rib 13 being bowed outwardly as indicated at 14, while the lower portion 15 thereof is made straight (see Fig. 6).

Each of the ribs 13 is provided at the free end of its bowed section 14 with an integral flat straight tongue member 16, having no side wings. A pair of opposed outwardly formed locking nibs 17 are formed on the edges of the side wings of the lower straight section 15 of each rib adjacent the junction point of said straight section 15 and the bowed section 14. The nibs 17 serve to hold the rib 13 securely in assembled position with respect to an inverted channel-shaped spacing ring 18, having a plurality of uniformly spaced apertures 19 in which said ribs 13 are adapted to be engaged.

The ring 18 is adapted to be positioned at the junction of the bowed section 14 and straight section 15 of each rib 13 with the nibs 17 on said ribs located within the groove of the channel shaped ring 18. The spacing ring 18 is preferably made from an initially flat metal annular ring and formed up into U-shaped cross-section for producing a stiff strong construction.

The upper ends 16 of the ribs 13 are rigidly connected to a flat apex ring 20 having a central drain aperture 21 and provided with a plurality of uniformly spaced notches 22 formed in the outer periphery thereof, as best shown in Fig. 5. The upper shouldered ends of the bowed channel sections 14 of the ribs 13 are adapted to be interfitted within the notches 22, and the tongues 16 are then bent downwardly and outwardly around the inner periphery 23 of said ring 20, (see Fig. 4).

After all of the ribs have been assembled in the apex ring 20, a raised circular rib 24 is formed upon the intermediate part of said ring 20, and grooves 25 and beads 26 are formed simultaneously on the upper and lower wings respectively, of the tongue members 16, as shown in Figs. 2 and 4. This construction greatly increases the strength and rigidity of the device.

Assembly

In the assembly of the strainer 10, the bowed sections 14 of each rib 13 will first be inserted

- through the apertures 19 of the lower channel-shaped spacing ring 18 from the under side thereof until the pair of nibs 17 previously formed on said rib engages the underside of the body of said 5 inverted ring 18 (see Fig. 3). The upper free end of the bowed section 14 of each rib will then be positioned within a notch 22 of the apex ring 20, and the integral tongue 16 will be bent about said ring 20 as previously explained.
- 10 After all the ribs 13 have been thus assembled to form the complete strainer 10, the raised circular rib 24 will be formed in the apex ring 20 and the interfitting grooves 25 and beads 26 will be simultaneously formed in the upper and lower 15 parts of the looped tongues 16 by means of suitable tools, not shown.

In the modified form of the invention shown in Fig. 7, the construction is identical in all respects with the first form of strainer shown in 20 Figs. 1 to 6, except that a lower rib-spacing ring 27 is employed having a plurality of uniformly spaced exterior loops 28 for receiving the lower straight portions of the ribs 13. The modified ring 27 is constructed from an initially channel-shaped ring similar to the ring 18, but after all the ribs 13 have been assembled therein, the sections 29 of the outer wing between said ribs 13 are crimped inwardly into contact with the inner wing of said ring 18, thus causing the ribs 13 to 30 be tightly clamped in assembled position.

While there have been disclosed in this specification two forms in which the invention may be embodied, it is to be understood that these forms are shown for the purpose of illustration only, 35 and that the invention is not to be limited to the specific disclosures but may be modified and embodied in various other forms without departing from its spirit. In short, the invention includes all the modifications and embodiments coming 40 within the scope of the following claims.

Having thus fully described the invention, what is claimed as new, and for which it is desired to secure Letters Patent, is:

1. In a down spout strainer, a plurality of up- 45 standing ribs having lower straight sections forming a cylindrical portion of the strainer, and upper outwardly bowed sections to form a cage-

like domed section of said strainer, a rib spacing ring embracing the lower straight sections of said ribs, and an upper flat apex ring having a central drain aperture attached to the upper ends of said ribs, said apex ring having a plurality of 5 spaced exterior circumferential notches for receiving the upper free ends of said ribs which are passed down through said central aperture.

2. In a down spout strainer, a plurality of up- 10 standing ribs having lower straight parallel sections and upper outwardly bowed sections, a rib spacing ring of inverted channel shape engaging the straight portion of said ribs, and a flat apex ring provided with exterior notches having interlocking engagement with the upper free ends of 15 said ribs.

3. In a down spout strainer, a plurality of up- 20 standing ribs having lower straight parallel sections and upper outwardly bowed sections, said ribs being of U-shaped channel cross-section, a 25 rib-spacing ring engaging the ribs at the junction of said straight and bowed sections, an apex ring having interlocking engagement with the upper free ends of said ribs, and nib means formed on the straight section of said ribs to hold said spac- 25 ing ring against the bowed section of said ribs.

4. In a down spout strainer, a plurality of up- 30 standing ribs having lower straight sections and upper outwardly bowed sections, said ribs being of U-shaped channel cross-section, and a rib- 35 spacing ring positioned at an intermediate section of said ribs, said ring being of inverted channel-shape having uniformly spaced apertures through which said ribs are engaged, the intermediate portion of the outer wall of said channel- 35 shaped ring between said ribs being collapsed against the inner wall of said ring whereby a series of rib-embracing loops are provided for rigidly clamping said ring to said ribs.

5. A rib for a down spout strainer comprising 40 a straight section and an integral bowed section, said rib being formed from strip metal bent into U-shaped cross-section, said rib having a flat locking tongue integrally formed at the free end of said bowed section. 45

CARL L. WEYAND.
